UNITED STATES PATENT OFFICE.

GEORGE W. PIERCE, OF DAVIS, CALIFORNIA, ASSIGNOR TO CALIFORNIA ALMOND GROWERS EXCHANGE, OF SAN FRANCISCO, CALIFORNIA, A CORPORATION OF CALIFORNIA.

APPARATUS FOR BLEACHING ALMONDS.

1,382,850.

Specification of Letters Patent. Patented June 28, 1921.

Application filed August 24, 1920. Serial No. 405,703.

To all whom it may concern:

Be it known that I, GEORGE W. PIERCE, a citizen of the United States, residing at Davis, in the county of Yolo and State of California, have invented certain new and useful Improvements in Apparatus for Bleaching Almonds, of which the following is a specification.

The hereinafter described invention relates to an apparatus for the bleaching or blanching of almonds, preparatory to the marketing thereof, and the same comprises inter-connected associated automatically operated instrumentalities for receiving the almonds, steaming or moistening of the same, delivering the moistened almonds to rotary means for the agitation thereof while being subjected to the action of the fumes of sulfur, and finally discharging the bleached almonds. The general objects of the invention are to provide automatically operated means for efficiently handling or treating a number of tons of almonds per hour; to materially increase the daily output of the bleaching plant, to reduce the cost of treating the almonds and to dispose of the manual handling of the almonds during the processing thereof. With these and other objects which will readily present themselves to those conversant with the art of bleaching or blanching of almonds, the invention will be understood by reference to the accompanying sheets of drawings, disclosing a preferred embodiment of an apparatus for the carrying out of the invention and wherein—

Figure 1 is a side view in elevation of the apparatus partly broken away, disclosing the moistening means for the almonds to be treated, the rotary agitator which receives the moistened almonds, and the mechanism for controlling the feed of the almonds from the moistening means into the rotary agitator.

Fig. 2 is an end elevation of the apparatus viewed from the drive end thereof.

Fig. 3 is a similar view of the apparatus viewed from the opposite or discharge end thereof.

Fig. 4 is a broken part sectional end elevation, disclosing the rotary agitator, the swinging gate controlling the discharge of the almonds into the agitator, the means for actuating said gate, the gate controlling the admission and discharge of almonds relative to said agitator, and the means for con-

trolling the opening and closing movements of said gate.

Fig. 5 is a broken irregular vertical sectional view taken on the line 5—5—Fig 4 of the drawings and viewed in the direction of the arrows, disclosing the means for controlling the locking and unlocking of the swinging gate for the rotary agitator.

Fig. 6 is a broken detail part sectional view of the means for actuating the swinging gate 65 of the hopper containing the almonds for delivery into the rotary agitator.

Fig. 7 is a vertical sectional end elevation taken on line 7—7—Fig. 1 of the drawings and viewed in the direction of the arrows, 70 disclosing the hopper for receiving the treated almonds and such of the untreated almonds as flow over the rotary agitator after the gate thereof has passed beyond the discharge outlet of the main feed hopper and 75 prior to the closing of its outlet gate.

In the present case, the rotary agitator is illustrated and will be described as adapted to receive and treat a batch of almonds, being to such extent an intermittently operating apparatus. This, however, is an immaterial feature, inasmuch as the said rotary agitator may be an open ended one, receiving the almonds to be treated at one end and discharging the same therefrom as treated 80 almonds from the opposite open end. Inasmuch as the invention resides in automatically operated means for receiving and treating the almonds to the action of the fumes of sulfur, while maintained in a condition of 85 90 agitation, I do not wish to limit or restrict the apparatus invention to any particular constructed form of rotating agitator.

In the drawings, Figs. 1, 2, 4 and 7, the numeral 1 is used to designate the main 95 frame of the apparatus, which in the present case constitutes a closed bin, approximately sixteen feet in length. Within the said bin is located an upper almond receiving hopper 2 for the almonds to be treated, and a lower 100 hopper 3 for receiving the treated almonds and such of the untreated ones as discharges from the main hopper 2 after the closure of the gate of a rotating agitator for receiving the almonds to be treated. The main hopper 105 2 is supported in any suitable manner and is separated from or situated a distance above the lower hopper 3. Between or intermediate of these hoppers is located or positioned a longitudinally disposed rotary agi- 110

tator 4, composed of longitudinal spaced bars or members 5 united at their ends by the circular end plates 6, which plates serve in the present case to close the ends of the agitator. As noted by reference to Figs. 4 and 6 of the drawings, the rotary agitator is an open or mesh cylinder, somewhat similar to an ordinary grizzly, the openings thereof being of such size as to prevent the escape of 10 almonds of proper size therethrough. The said cylindrical agitator is approximately sixteen feet in length and six feet in diameter, the same being mounted on a longitudinal disposed shaft 7, the ends of which work in suitable bearings and project beyond the end walls of the bin 1, the interior of which bin and within which the said agitator revolves 15 constituting the sulfuring chamber 8 of the apparatus.

20 Rotation is imparted to the shaft 7, by means of a longitudinally disposed driven shaft 9, which shaft is located outside of the bin 1 and carries at each end a small sprocket gear 10. These gears are connected to the 25 larger sprocket gears 11 secured to each end of the shaft 7, by means of the sprocket chains 12, Figs. 1, 2 and 3 of the drawings. The shaft 9 is driven from the drive shaft 13 through the medium of suitable intermeshing gears, power being applied to the 30 said shaft 13 by a drive belt 14 working over a belt pulley 15 mounted on the said drive shaft.

Outside of the bin 1 is located a transversely disposed downwardly inclined cylinder 16, into the upper end of which the almonds to be processed are delivered in any suitable manner. This cylinder is known as a steaming or moistening cylinder, the 35 almonds as moved therethrough toward the lower discharge end being subjected to the action of either steam or water sprayed thereon from the perforated pipe 17, extended within the cylinder. The moistened almonds 40 discharging from the lower end of the said cylinder (which has rotation imparted thereto by any suitably connected form of drive means), are delivered within a vertically disposed chute 18 and onto an endless bucket 45 elevator 19 working therein and by means of which the preliminarily treated almonds are elevated and discharged within the parallel feed troughs 20, arranged a distance above the main receiving hopper 2, Figs. 1, 2 and 3 50 of the drawings. Within each of the feed troughs 20 is located a worm conveyer, not shown, driven by a drive belt (not shown), working over a belt pulley 21 secured to one end of each worm shaft. These worms 55 propel the almonds along the feed troughs until the same reach the discharge outlets cut therein, from which are downwardly extended the distributing chutes 21, there being two of said chutes for each trough. These 60 chutes discharge directly into and distribute 65

the almonds even throughout the length of the receiving hopper 2, which in length is coextensive with that of the revolving agitator. By thus distributing the almonds substantially evenly throughout the length of 70 the hopper 2, the banking or overcrowding of the same at any given point is avoided.

The rotary agitator 4 is provided with a pivotally mounted swinging gate 22, Figs. 4 and 6 of the drawings. This gate extends for 75 the full length of the agitator and is pivotally mounted with respect to the end walls or plates 6 thereof, and the same is overweighted by means of a weight member 23 applied thereto, so that when released from locked 80 position the same swings downwardly by gravity to open position, Fig. 6 of the drawings. By means of two lock pins 24, slidably through guide openings 24' formed through each of the end plates 6 of the agitator, the 85 said gate 22 is held in locked position, the inner ends of the lock pins 24 at such times fitting within the pin sockets or recesses 25 formed in each end of the gate 22.

The lock pins 24 are moved into and out of engagement with the swinging gate 22 during the rotary movement of the agitator 4, by means of two pivotally mounted wedge or cam plates 26, which at times during the rotary movement of the agitator are thrown 90 inwardly to lie within the path of travel of and to engage simultaneously cross pins 26' projecting from the heads of the lock pins 24. The said wedges or cams 26 are disclosed in open position by full lines and in closed 95 position by dotted lines by Fig. 5 of the drawings, they being pivoted at their lower end to the frame of the apparatus. These wedges or cams are actuated by the bellcranks 27, which in turn are operated by means of the 100 crank lever 28. The free inner end of said levers (there being one at each end of the machine) carry a cam follower roll, which works within a cam groove 29 cut in the face of each cam 29', Fig. 2 of the drawings. 105 Only one cam 29 and crank lever 28, are disclosed, but it will be understood that corresponding parts are situated at each end of the apparatus, but being duplicates, as well as the means for actuating the cam disk 29', 110 the illustration and description of one will suffice for the other. Each cam disk 29' is driven from a gear 30, which meshes with a gear pinion 31, on the shaft for the cam 29', and a gear 32, which latter gear is driven 115 from the shaft 9 by means of a sprocket chain 32' working over a sprocket wheel on said shaft and a sprocket wheel mounted on the shaft for the gear 32. The gear relation of the connected driven gears for imparting 120 rotary motion to the cam disks 29' is such in the present case, that the said cams make one complete rotation to every eighteen revolutions of the rotary agitator, so that on the 125 eighteenth revolution of the said agitator the 130

follower roll carried by the crank levers 28 move or ride on that portion of the cam groove of the cams 29' as act to throw the same for operating the bell-crank 27 to throw 5 the wedges 26 inwardly, so as to lie within the path of travel of the cross pins 26' of the lock pins. With the wedges 26 thus positioned, disclosed by dotted lines—Fig. 5 of the drawings, as the rotation of the agitator continues, 10 the cross pins 26' ride over the inclined surface of the wedges and gradually withdraw the lock pins 26 passing between said wedges from locked engagement with the gate 22 of the agitator, when the same swings by gravity 15 into a vertical position to open the agitator and permit the escape of the sulfured almonds therefrom, which flow downwardly into the receiving hopper 3 situated in the lower portion of the bin 1 and below the revolving agitator.

The central discharge outlet or open bottom of the main receiving hopper 2 is provided with a closure gate 33, carried by the swinging brackets or arms 33', the trunnions 33² of each arm working in bearings 34 of the frame structure. Figs. 4 and 5 of the drawings. To the lower end of each swinging arm or bracket 33' is fulcrumed for vertical movement a transversely disposed lever 34', the notched tail extension 34² of which is normally in locked engagement with a longitudinally disposed lock bar 35, being held in such position by the overweight of that portion of the lever in 30 advance of its fulcrum point.

The lever 34' is thrown from locked position to release the gate 33, by means of the arcuated levers 36, one being pivoted to the inner wall surface of each of the end plates 40 6 of the rotary agitator, the free end of said levers 36 overlying the face of the swinging gate 22 for said agitator, Figs. 4 and 6 of the drawings. Each lever 36, only one of which is illustrated, is provided with a projecting transversely disposed pin 36' for engagement with the shoulder 37 of the fulcrumed lever 34' during the rotary movement of the agitator, when its gate 22 stands in open position. On the release of the gate 50 22, the same as swung into open position engages with the inner face of the levers 36 and swings the same outwardly, so as to place the pins 36' of the levers 36 in position to engage with the shoulder 37 of the levers 34'. As thus positioned, as the movement 55 of the agitator carries the levers 36 into the position disclosed by Fig. 6 of the drawings, the pins 36' thereof first engage with or bear against the shoulder 37 of the levers 34' and as the agitator continues its movement of 60 rotation, the pressure exerted onto the levers 34' is such as to first swing upwardly the inner end thereof and lowering the tail extension 34² to release the same from engagement with the lock bar 35 and thus free the

swinging gate 33 of the hopper 2. With the pins 36' of the pivoted levers 36 still in engagement with the shoulder 37 of the levers 34' and the agitator continuing its movement of rotation, the pressure exerted thereon forces over the levers 34' to swing the arms 33', which carrying therewith the gate 33 moves the same to gradually open the discharge outlet of the hopper 2 and permit the charge of almonds contained therein to 70 discharge into the rotary agitator through its open gateway 37', which at such time is moving beneath the discharge outlet of the hopper 2. The discharge of the almonds into the agitator continues until the gate 33 is swung over its full distance, during which movement the upper notched end 38 of a pivoted bell crank 38' is gradually raised by the engagement of the moving levers 34', to position the notched end 38 of the bell 75 crank 38' for engagement with the edge of the swinging arms 33' and thus hold the gate 33 in locked open position, disclosed by dotted lines—Fig. 4 of the drawings. The swinging gate 33 remains held in its 80 open locked position until the arcuate levers 36 are advanced to engage with the lower arm 38² of the bell cranks 38', and release the pin 36' thereof from engagement with the shoulder 37 of the levers 37', which arms 85 38² are gradually raised by the pressure of the outwardly swung levers 36 thereagainst, in order to throw downwardly the upper arm of said bell cranks to release the gate 33, when the same swings by gravity to normal 90 position, carrying therewith the lock levers 34', the notched tail extension 34² of which swings upwardly into engagement with the lock bar 35 and thus holds the said gate 33 locked in closed position. During 95 this closing action of the said gate, the projecting end of the gate 22 for the rotary agitator bears against the face of the fixed cam plate 39 inwardly projected from the frame of the apparatus and the same is 100 gradually swung inwardly to closed position and the cross pin 26' of the lock pins 24 positioned for movement against the under surface of the inclined cams or wedges 26 for gradually forcing inwardly the lock pins 24 to place the inner end thereof into the sockets or recesses 25 of the gate 22, in order to hold the same locked in closed position. By the time the gate 22 is moved to closed 105 position, the cam 29' controlling the action of the associated crank levers 27 and 28, will have moved to throw the crank 28 to reset or restore the wedges 26 to normal position, so that the cross pin 26' of the lock pins 24 will bear against the under face of the said wedges or cams 26. In this outwardly swung position the wedges 26 will 110 remain until the rotary agitator completes its eighteenth revolution, when the same, as previously described will be thrown in- 115

wardly to engage with the said cross pins 26' to release the lock pins 24 and permit the opening of the gate 22, after which the action of the parts previously described take 5 place.

Sulfur fumes for the sulfuring of the almonds contained in the revolving agitator is admitted within or supplied to the sulfuring chamber 8 by means of the supply pipe 10 41, Fig. 2 of the drawings, the fumes so supplied entering through the spaces of the rotary agitator and coming into direct contact with the batch of almonds under treatment and during the agitation thereof for 15 the bleaching of the same.

The described working parts are entirely automatic in their operation and are actuated in timed relation, and the agitator is of such size as to hold and treat at one time 20 approximately one and one-half tons of almonds, which almonds are throughout the process of bleaching maintained in a perfect state of agitation. About seventeen minutes are required to process one batch of 25 almonds, so the machine is capable of processing approximately five tons per hour. After the closing of the gate for the agitator and prior to the closing of the gate for the main supply hopper 2, there is usually an 30 escape of almonds from the latter, commonly known as dribbling. These almonds fall onto the surface of the rotating agitator and must be returned to the feed supply mechanism. For this purpose, it is arranged 35 that the receiving hopper 3 be divided by a vertical diaphragm 42 into two compartments A—B, Fig. 7 of the drawings, of which compartment B receives the treated or bleached almonds and A the untreated or 40 dribble almonds to be returned to the feed means. There is a deflector gate 43 arranged to direct the flow of almonds relative to the compartments A and B, which gate during the rotation of the agitator with almonds 45 therein under treatment is thrown to close the entrance-way to the compartment B and open the passage-way to the compartment A. This gate is thrown into the position disclosed by Fig. 7 of the drawings, when the 50 gate 22 is opened to permit the discharge of treated almonds by means of the trip lever 44, actuated by the movement of the bell-crank 28, Figs. 2 and 7 of the drawings. From the lever 44 is extended a cord, cable 55 or chain 44', which is attached at its lower end to a transversely movable cord 44'', which is drawn outwardly by the action of the lever 44 to throw the gate 43 to open the passage-way leading to compartment B by 60 means of the suspended weight 45, when the gate 22 of the agitator is swung to open position, and is drawn outwardly to close said passage-way and open the passage-way leading to compartment A when the gate of 65 the rotary agitator is closed, so as to permit

of the dribbling almonds to flow into said compartment B.

On the opening of the swinging gate 33 controlling the discharge of almonds from the receiving hopper 2 into the rotary agitator 4 of the apparatus, it is desirable that the flow of almonds into said hopper be cut off. For this purpose the cut-off gate 50 is provided, Figs. 1, 2, 3, 4 and 5 of the drawings, said gate extending the full length of 75 an inclined runway 21^a, and being supported or carried by the swinging arms 51 pivotally mounted relative to the frame of the apparatus, and the same are thrown in order to lower the gate 50 to lie in front of the 80 runway 21^a.

When the gate 33 of the hopper 2 is opened to permit the flow or discharge of almonds therefrom, the feed of almonds into said hopper should be discontinued. For 85 this purpose there leads from cut-off gate 50 the upwardly extended connecting rods 52, which are united at their upper ends to the bell-crank 52', Figs. 1, 2, 3 of the drawings. These bell-crank are connected to slide 90 plates 53 of the feed troughs 20, which when withdrawn by the action of the bell-crank on the downward movement of the cut-off gate 50, open the discharge outlets cut in the 95 said troughs at the rear of the outlets communicating with the distributing chutes 21, with the result that the almonds moving through the troughs fall through said cut-outs onto the downwardly extended chute 54 directed thereby into the bin and work 100 downwardly over the surface of the rotary agitator until discharged into the compartment A for the unbleached and dribbled almonds. Of course, as the cut off gate 33 is opened to permit the flow of almonds into 105 the agitator 4, reverse movement is imparted to the bell cranks 53 and the slides are thrown to close the discharge outlets, so that the almonds are moved through the troughs 20 until the outlets for the distributing 110 chutes 21 are reached.

The non-treated or unbleached almonds delivered into compartment A of the hopper 3, are discharged therefrom through the restricted outlet *a* by means of the rotating discharge roll 55, Fig. 7 of the drawings. The almonds escaping through the restricted outlet *a* fall onto an endless traveling belt conveyor 56 and by means thereof discharged at one end of the apparatus into an 115 upwardly inclined chute 57 and by means of an endless elevator 58 working therein conveyed upwardly and discharged into the chute 18 to be elevated therein by the endless conveyor 19 with the almonds to be delivered into the feed chutes 20, Fig. 3 of the drawings. The treated or bleached almonds are fed from the compartment B of the hopper 3 through the restricted passage-way *b* by means of the feed roll 59 and fall onto 120

115

120

125

130

the endless traveling belt conveyer 60 and discharged thereby into a delivery chute 61, being elevated therein to a suitable place of deposit by means of an endless elevator 62 working therein.

Motion is imparted to the shaft of the feed roll 55 for delivering the unbleached almonds through the restricted passage-way *a* of the hopper 3, by means of a belt 63 working over a pulley on said shaft and a belt pulley on the drive shaft 13, Fig. 3 of the drawings, while rotation is transmitted to the feed roll 59 by means of the belt 64 working over a belt pulley mounted on the shaft of said roll and an idler pulley 65 driven from the belt 63.

The endless belt conveyers 56 and 60 work over belt rollers arranged at each end of the machine and are driven by any suitable means, for instance, through the medium of the driven belts 66-67, Fig. 1 of the drawings.

Each compartment A and B of the hopper 3 is provided with a swinging gate section 68, by means of which the passage-ways *a* and *b* may be controlled, said gates being adjustable from the outside of the apparatus by hand actuated adjusting rods 69. Fig. 7 of the drawings.

As stated, the working parts of the apparatus operate in timed relation; all almonds flowing through the machine and not falling into the rotary agitator being returned as almonds to be treated to the feed troughs; the almonds while under treatment are maintained in a condition of agitation and in direct contact with the flowing fumes of sulfur; the operation of the apparatus is automatic and capable of handling and successfully bleaching a large quantity of almonds per day; there is no waste of the almonds delivered for treatment, and in general the apparatus provides efficient means for the treatment of the almonds and at a materially reduced cost over the means for bleaching almonds employed previous to the present invention.

The cut-off gate 50 is normally held in raised position by the member 68 carried by the swinging arms 33' for the gate 33. As the gate is swung to open position, the edge of the member 68 moves away from the arms 51, when the gate 50 lowers by gravity. On the return movement of the swinging gate 33, the pressure of the member 68 against the pivoted arms 51 tends to raise the same to lift the cut-off gate 50, and to aid therein and relieve the swinging gate 33 of undue strain; weight attached to a chain or cord 69 is provided, the weight of which does not quite counter-balance that of the cut-off gate 50.

An apparatus has been illustrated and described as the preferred embodiment for the carrying out of the invention, but I do not

wish to be understood as restricting or limiting the invention to the described details of construction, but, on the contrary wish to be understood as claiming the same as broadly as the state of the art will warrant. 70

Having thus described my invention, what I claim as new and desire to protect by Letters Patent is:—

1. The combination with an apparatus provided with a sulfuring chamber, of an open cylindrical agitator rotatably mounted therein, means for imparting continuous rotary movement to said agitator, and means for controlling the feed of almonds within and the discharge therefrom from within the agitator during the rotary movement thereof.

2. The combination with a sulfuring chamber of an almond bleaching apparatus, of an agitator mounted therein for rotation, mechanism for driving said agitator, and means for controlling the feed of almonds within and the discharge thereof from within the agitator.

3. The combination with the sulfuring chamber of an almond blanching apparatus, of a rotary agitator mounted therein, feed means for supplying almonds for treatment to said agitator, and mechanism for returning the dribble or untreated almonds to said feed means.

4. An apparatus for the described purpose, the same comprising an open cylindrical agitator mounted for rotation within a sulfuring chamber, and means for delivering almonds within said agitator during the rotary movement thereof.

5. An apparatus for the described purpose, the same comprising an open cylindrical agitator mounted for rotation within a sulfuring chamber, mechanism for continuously feeding almonds to be processed, and means for controlling the feed of said almonds into and from said agitator.

6. An apparatus for the described purpose, the same comprising an open agitator mounted for rotation within a sulfuring chamber and adapted to receive and maintain almonds under agitation during the processing thereof, and means for supplying almonds to said cylinder and controlling the discharge therefrom.

7. In an apparatus for the described purpose provided with a sulfuring chamber, of agitating means situated within said chamber for receiving almonds and maintaining the same under agitation while subjected to the action of sulfur fumes within the sulfuring chamber, and means for controlling the feed of almonds for processing to said agitator.

8. In an apparatus for the described purpose, the combination with an agitator for receiving and maintaining under agitation almonds to be processed while subjected to

the action of sulfur fumes, of means for delivering almonds for treatment to said agitator.

9. In an apparatus for the described purpose, the combination with an agitator for receiving and maintaining almonds under agitation while subjected to the action of the fumes of sulfur, means for imparting motion to said agitator, and mechanism for controlling the feed of almonds to the agitator.

10. In an apparatus provided with a sulfuring chamber, of a rotary agitator mounted within said chamber, means for imparting rotation to the agitator, a swinging gate therefor, devices controlling the locking and release of said gate at pre-determined times during the rotary movement of the agitator, and mechanism controlling the delivery 20 of almonds to be processed to said agitator.

11. In an apparatus provided with a sulfuring chamber, of a rotary agitator mounted within said chamber, means for imparting rotation to the agitator, a swinging gate 25 therefor, devices controlling the locking and release of said gate at pre-determined times during the rotary movement of the agitator, mechanism controlling the delivery of almonds to be processed to said agitator, and 30 means for receiving and returning the dribbled or unprocessed almonds passing through the apparatus to the feed means.

12. The combination with an agitator mounted for rotation within a sulfuring 35 chamber, a hopper for receiving almonds to be processed, means controlling the discharge of almonds from said hopper into the agitator, and mechanism for imparting rotary movement to the said agitator.

40 13. The combination with an open cylindrical agitator mounted for rotation within a sulfuring chamber, of means carried by the agitator for retaining almonds therein and controlling the discharge therefrom, and 45 means for feeding almonds to be processed within the agitator.

14. In an apparatus for the described pur-

pose, the combination with a cylindrical agitator mounted for rotation within a processing chamber, of a feed hopper for almonds 50 provided with a controllable outlet gate, and means acted on by the rotary agitator for actuating said gate to open and close said hopper for controlling the feed of almonds to the agitator.

55 15. In an apparatus for the described purpose, the combination with a cylindrical agitator mounted for rotation within a processing chamber, of a feed hopper for almonds provided with a controllable outlet gate, 60 means acted on by the rotary agitator for actuating said gate to open and close said hopper for controlling the feed of almonds to the agitator, and mechanism for receiving and returning the dribble or unprocessed 65 almonds to said feed hopper.

16. In an apparatus for the described purpose provided with a processing chamber, of a main hopper for almonds and a receiving hopper for treated almonds separated therefrom, an open rotary agitator for receiving 70 almonds to be processed interposed between said hoppers and disposed within the processing chamber, a controllable gate for the main hopper, means thrown into action at 75 times during the rotary movement of the agitator for controlling the opening and closing of the gate for the main hopper, devices for separating the delivery of the treated and the untreated almonds relative 80 to the receiving hopper, and means for removing the untreated almonds from said hopper for returning the same to the main hopper.

17. An apparatus for bleaching almonds, 85 the same comprising a housing adapted to be filled with bleaching fumes, an open almond holding cylinder rotatably mounted within said housing and arranged to receive and discharge almonds, and means for the feeding 90 to said cylinder almonds to be treated.

In testimony whereof I have signed my name to this specification.

GEORGE W. PIERCE.
